UNITED STATES PATENT OFFICE.

WILLIAM R. WHITLOCK, OF ABERDEEN, WASHINGTON, ASSIGNOR TO WHITLOCK UNIVERSAL CARRIAGE CO., OF ABERDEEN, WASHINGTON, A CORPORATION OF WASHINGTON.

HIGH-LINE CARRIAGE.

Application filed October 19, 1927. Serial No. 227,211.

The present invention relates to a high line carriage particularly adapted for hauling logs, and has for its prime object to provide a structure wherein it is possible to 5 hoist a log to any convenient height, and haul the same safely without injury to any surrounding timber and the like. In the old method of hauling in logs by the high line, the logs moved towards their destination before they had cleared the ground, causing much breakage and the loss of small trees by the logs dragging over them. The present invention overcomes these undesirable features.

15 A still further important object of the invention resides in the provision of a carriage of this nature which is simple in its construction, inexpensive to manufacture, strong and durable, thoroughly efficient and 20 reliable in operation, and otherwise well adapted for the purpose for which it is designed.

With the above and numerous other objects in view as will appear as the description 25 proceeds, the invention resides in certain novel features of construction, and in the combination and arrangement of parts as will be hereinafter more fully described and claimed.

30 In the drawing:—

Figure 1 is a side elevation of the carriage embodying the features of my invention.

Figure 2 is a top plan view thereof.

35 Figure 3 is a vertical transverse section taken substantially on the line 3—3 of Figure 1.

Figure 4 is a vertical longitudinal section taken substantially on the line 4—4 of Figure 2.

40 Figure 5 is a vertical longitudinal section taken substantially on the line 5—5 of Figure 2.

Figure 6 is an end elevation of the carriage.

45 Figure 7 is a detail elevation of the clutch structure.

Figure 8 is another view thereof showing the same engaged, and,

50 Figure 9 is a transverse vertical section through the clutch structure.

Referring to the drawing in detail, it will be seen that three plates, 5, 6 and 7 are held together in spaced parallel planes by suitable bolts 8 or other fastening elements. A pair of grooved rollers 10 and

11 are mounted respectively on shafts 12 and 13. The roller 11 has formed on one side thereof a pin wheel 14 which is rotatable therewith and extends through an opening 15 formed in the upper edge of the 60 plate 6. These grooved rollers 10 and 11 are adapted to ride on the high line 16. A grooved roller 17 is journaled on the shaft 18 between plates 5 and 6 below the grooved roller 10 and has trained thereover a pull and hoist line 19 which is trained under the pulley of the hoisting block 20 and is anchored as at 21 in an arm 22 which is pivoted as at 23. A clutch structure denoted generally by the letter 70 C comprises a plurality of blocks 24 with notches 25 therein through which is trained the high line 16 between the rollers 10 and 11. These blocks are connected together at their upper and lower ends respectively 75 by bars 27 and 28. One of the end blocks 24 has an extension 29 with a slot 30 formed therein. The bar 28 is extended at the end opposite to the block 24 having the extension 29. The extremity of the extended 80 portion of the bar 28 is pivoted as at 31 to the arm 22. A pin 33 between the plates 5 and 6 extends through the slot 30. A shoulder 34 is mounted between the plates 85 5 and 6 and has a recess 35 in the lower portion thereof to receive the upper end of the block 20. Guides 36 are provided to lead the block so that the upper end will seat in the recess 35. A projection 37 is provided on the upper ends of the block laterally thereof and moves in a vertical slot 38 provided in the plate 6 extending vertically from the lower edge thereof. A pair of spaced parallel guides 39 are mounted on the plate 6 one to each side of the upper portion of the slot 38. A second pair of guides 40 are disposed in spaced parallelism on the plate 6 above the guides 39. These guides 39 and 40 are separated by a slot 41 in the plate extending horizontally.

90 A Z-shaped member 42 is movable between the guides 39 and 40. A pair of pins 43 and 44 project laterally from the lower portion of the clutch structure C as is shown to advantage in Figures 3 and 4 105 and projects through the slot 41 to be disposed one on each side of the Z-shaped member 42. The weight of this Z-shaped member 42 is sufficient so that its intermediate portion would function as a cam 110

when the Z-shaped member gravitates downwardly and moves the bar 28 to pivot the blocks 24 to their locking position as shown in Figure 8. The block with its projection 37, however, holds the Z-shaped bar 42 in a raised position when the block is raised. However, as soon as the block lowers, the Z-shaped member tends to immediately lock the clutch on the high line 16 so as to prevent any movement of the carriage. It will also be seen that as the block 20 moves down to the dotted line position shown in Figure 5, the cable 19 will pass over the pivot 23 so as to tend to swing the arm 22 to the dotted line position shown in Fig. 5 and further assist in the locking of the clutch structure.

A latch 50 is pivoted on a pin 51. This latch 50 has pivoted extensions 52 and 53 at its ends. The extension 53 is in the downward path of the projection 37 so that in order for the block to lower, it will be necessary for the latch 50 to swing to the dotted line position shown in Figure 4. This latch is prevented from swinging to this position by means of a bolt 54 slideable in a way 55. This bolt is slideable by one end of a lever 56 projecting thereinto being pivoted as at 57 and having its upper extremity engaged with the pins of the pin wheel 14. Springs 58 tend to hold the lever in a vertical position.

A line 59 is attached to a block 20 so as to return the carriage to the position for engaging the logs. When in the proper position, the cable 19 is slackened thereby allowing the block 24 and simultaneously allowing the Z-shaped bar 42 to pull so that the pin 44 will tend to lock the clutch and simultaneously the slackening of the cable will allow the arm 22 to swing over to the dotted line position to which it is urged by the clutch thereby assuring the locking of the clutch.

Now the movement of the carriage by the cable 59 rotates the pin wheel 14, in Figure 4, in a counter-clockwise direction so that the bolt 52 is slid out of the way of the latch extension 53 so that the latch 50 may fit into the dotted line position and allow the block to move downwardly. When the block is down, and the log is engaged thereon by means of a chain or in any other desired manner, the cable 19 is pulled by a winch or other structure so as to hoist the block 20. As the block moves upwardly into the guides 32 and finally comes to rest in the shoulder 34 the further pulling of the cable 19 will cause the swinging of the arm 22 to its full line position thereby releasing the clutch and simultaneously, the projection 37 will engage the Z-bar 42 so that the intermediate portion thereof will function as an inclined plane or cam on the pin 42 and will unlock the clutch.

The further pull on the cable 19 will pull the carriage to the left as shown in these drawings which rotates the pin wheel in a clockwise direction so that the bolt 54 is extended over the latch extension 52 so that the block cannot fall as long as the carriage is moved in this direction.

It is thought that the construction, operation, utility, and advantages of this invention will now be quite apparent to those skilled in this art without a more detailed description thereof. The present embodiment of the invention has been disclosed in detail merely by way of example since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:—

1. A carriage of the class described comprising a body, means in the body for moving over a high line, a clutch structure in the body to engage the high line, a pair of pins projecting from the clutch structure for operation thereof, a Z-bar having its intermediate portion extending between the pins, guide means for the Z-bar, a block, means for hoisting and lowering the block, said block having a projection for engaging the Z-bar to hold it in a raised position, said Z-bar being of sufficient weight to gravitate and actuate one pin by the intermediate portion functioning as an inclined plane to cause the clutch to lock on the high line, said projections being adapted to engage the bottom of the Z-bar to raise the Z-bar so that it will raise the other pin and release the clutch structure.

2. A carriage of the class described comprising a body, means in the body for moving over a high line, a clutch structure in the body to engage the high line, a pair of pins projecting from the clutch structure for operation thereof, a Z-bar having its intermediate portion extending between the pins, guide means for the Z-bar, a block, means for hoisting and lowering the block, said block having a projection for engaging the Z-bar to hold it in a raised position, said Z-bar being of sufficient weight to gravitate and actuate one pin by the intermediate portion functioning as an inclined plane to cause the clutch to lock on the high line, said projections being adapted to engage the bottom of the Z-bar to raise the Z-bar so that it will raise the other pin and release the clutch structure, a pivoted arm engage-

able with the clutch structure, and a hoisting cable associated with the block and connected with the arm.

3. A carriage of the class described comprising a body, means in the body for moving over a high line, a clutch structure in the body to engage the high line, a pair of pins projecting from the clutch structure for operation thereof, a Z-bar having its intermediate portion extending between the pins, guide means for the Z-bar, a block, means for hoisting and lowering the block, said block having a projection for engaging the Z-bar to hold it in a raised position, said Z-bar being of sufficient weight to gravitate and actuate one pin by the intermediate portion functioning at an inclined plane to cause the clutch to lock on the high line, said projections being adapted to engage the bottom of the Z-bar to raise the Z-bar so that it will raise the other pin and release the clutch structure, a pivoted arm engageable with the clutch structure, a hoisting cable associated with the block and connected with the arm, said clutch structure comprising a pair of bars, one of which has an extension pivoted to the arm, a plurality of blocks pivoted between the bar and having notches to receive the high lines, one of the blocks having an extension, and a pin and slot connection between the extension and the body. 55

5. A carriage of the class described comprising a body, means in the body for moving over a high line, a clutch structure in the body to engage the high line, a pair of pins projecting from the clutch structure for operation thereof, a bar inclined to the vertical extending between the pins, guide means for vertical movement of the bar, a block, means for hoisting and lowering the block, said block having a projection for engaging the bar to hold it in a raised position, said bar being of a sufficient weight to gravitate and engage one pin, to cause the clutch to lock on the high line, said projection being adapted to engage the bar, to raise the bar, so that it will engage the other pin and release the clutch structure. 60

4. A carriage of the class described comprising a body, means in the body for moving over a high line, a clutch structure in the body to engage the high line, a pair of pins projecting from the clutch structure for operation thereof, a Z-bar having its intermediate portion extending between the pins, 65

35 guide means for the Z-bar, a block, means for hoisting and lowering the block, said block having a projection for engaging the Z-bar to hold it in a raised position, said Z-bar 70

being of sufficient weight to gravitate and actuate one pin by the intermediate portion functioning as an inclined plane to cause the clutch to lock on the high line, said projecting pins being adapted to engage the bottom of the Z-bar to raise the Z-bar so that it will raise the other pin and release the clutch structure, a pivoted arm engageable with the clutch structure, a hoisting cable associated with the block and connected with the arm, said clutch structure comprising a pair of bars, one of which has an extension pivoted to the arm, a plurality of blocks pivoted between the bar and having notches to receive the high lines, one of the blocks having an extension, and a pin and slot connection between the extension and the body. 55

5. A carriage of the class described comprising a body, means in the body for moving over a high line, a clutch structure in the body to engage the high line, a pair of pins projecting from the clutch structure for operation thereof, a bar inclined to the vertical extending between the pins, guide means for vertical movement of the bar, a block, means for hoisting and lowering the block, said block having a projection for engaging the bar to hold it in a raised position, said bar being of a sufficient weight to gravitate and engage one pin, to cause the clutch to lock on the high line, said projection being adapted to engage the bar, to raise the bar, so that it will engage the other pin and release the clutch structure. 60

In testimony whereof I affix my signature.

WILLIAM R. WHITLOCK.
